COIN SELECTOR DEVICE

Harvey T. Larimore, Congress Park, Ill., assignor
to Kalva Venders, Inc., Chicago, Ill., a corpora-
tion of Illinois

Application July 14, 1943, Serial No. 494,595

7 Claims. (Cl. 194—1)

My invention relates to improvements in coin selecting devices for coin controlled machines. More specifically, it has reference to improvements in a known type of coin selector whereby two unlike coins must be deposited in a predetermined order to render the coin controlled machine operative. By use of my invention, for example, machines which normally operate upon the deposit of a nickel, may be made to require deposit of a penny and a nickel, in the order named, before becoming operative.

An object of my invention, therefore, is to provide a coin selector device which will require the deposit of two unlike coins in a predetermined order. A further object is the provision of a coin selector so arranged that if the coin which should properly be deposited second is deposited first, it will be returned. Another object is the provision of an arrangement by which the properly deposited first coin may be returned, if the second coin is not subsequently deposited and accepted.

A further object is the provision of a coin selector of the kind described, which permits subjecting the second coin to the usual tests for weight, size, magnetic character, bounce, etc., for the elimination of false coins or tokens.

With these and other objects in view, my invention consists in the construction, arrangement and combination of the various parts of my device whereby the objects contemplated are attained as hereinafter more fully set forth, pointed out in my claims and illustrated in the accompanying drawings, in which:

Figure 1 is an elevational view of one side of a coin selector embodying the principles of my invention.

Figure 2 is an end view of the same.

Figure 3 is a view of the side opposite that shown in Figure 1, and

Figure 4 is a fragmentary cross-sectional view taken on the line 4—4 of Figure 3.

For convenience in description, I shall refer to the specific embodiment of my invention in a so-called "six-cent" coin selector, requiring the successive deposit of a penny and a nickel. It will be understood, however, that the scope of the invention is such as to contemplate other combinations of coins.

In the drawings the reference number 10 indicates generally a mounting plate, which has a flange 12 turned up along one edge and a flange 14 along the opposite edge. A scavenger 16 is pivotally mounted on the plate, and cooperates with the main portion of the plate and with

flange 12 to form a vertical passage through which coins are guided after they fall into the selector from deposit chute 18.

In the passage thus formed are located the 5 projecting arm 20 of the undersize lever 22, and the projecting portion 24 of the undersize wire 26. The lever 22 is pivoted on rivet 28, and has a bell crank portion 30 (see Figure 2) extending from the pivot toward the flange 12. The undersize wire 26 is pivoted at 32 in bracket 34, and has a short lever extension 36 which engages portion 30 of lever 22.

The path traversed by nickels is shown in dotted lines (nickels at N¹, N² and N³ and their paths 15 a, b, c, d and e) in Figure 3, where it will be seen that the horizontal distance between the flange 12 and the normal position of arm 20 is such that a nickel could not pass without moving the arm to the right (transition from path a to path 20 b), the extent of the movement to the right being determined by the diameter of the coin. When arm 20 moves to the right, bell crank portion 30 is moved upward, causing a corresponding upward movement of lever extension 36 on undersize wire 26. The undersize wire is thus rotated 25 counterclockwise (as viewed in Figure 2) about its pivot 32. If the coin is of full diameter, the movement of the undersize wire will be just sufficient to withdraw the projecting portion 24 from the path of the coin. If the coin is undersize, the projecting portion 24 will not be fully withdrawn, and will stop the coin.

A light spring 38 bears upon the undersize wire, tending to hold its portion 24 in the coin path, and tending also, because of the interengagement of parts 30 and 36, to hold the undersize lever 22, with its projecting arm 20, in the position illustrated in Figure 3. Therefore a coin in moving arm 20 to the right must overcome 35 the force of spring 38, and the force of the spring 40 is so determined that a coin which is substantially under true weight cannot move the arm enough for the coin to pass by. Such a coin would be retained by arm 20.

45 Assuming the token to be of ample weight and diameter, the portion 24 of the undersize wire will be withdrawn sufficiently to let its leading edge pass. Immediately after the diameter of the token has passed the arm 20, however, the undersize wire will be released, and the rounded end of portion 24 will ride along the face of the token. Thus if the token has a hole in it, like a washer or certain trade checks, it will be caught and held as the washer or check traverses path C.

50 A coin or token passing the tests above de-

scribed drops to an inclined runway formed by a ledge or flange 40 on the underside of scavenger 16 (position N¹). It rolls down this runway (path c) in a narrow passage formed by a space between the plate 10 and a spaced bracket 42. The space is just enough to let a coin of true thickness pass freely. If the token is too thick, or is bent, it will wedge in the passage.

A permanent magnet 43 is provided, its poles lying flush with one side of the passage, and iron or steel tokens will be attracted and held by it.

A good nickel runs off the end of the flange 40, describing an arc as shown by path c in Figure 3 and falling on an anvil 44 (position N²). If the coin is a true one it rebounds freely, describing another curved course (d and f) which brings it through the coin outlet 46. From the outlet 46, it is guided into mechanism not shown, by which operation of the vending machine is effected. The mechanism may be arranged, for example, so that the coin forms a mechanical coupling between the manual operating lever and the goods delivery mechanism of the machine, the coin being discharged into a receptacle after the machine has been actuated.

If the token striking the anvil 44 is of some soft material such as lead, it will fall short upon rebound, dropping into the return chute 48.

For those tokens which may have been held in the mechanism at some intermediate point, a clearance means is provided by which the scavenger 16 is raised to free any tokens which may be held by it. Such tokens are deflected by curved flange 13 on plate 10 and finger 15 on bracket 17 into space 19 and roll along the bottom 21 of such space and into return chute 48.

The mechanism thus far described is that of a well known commercial device and is not my invention. My invention does lie, however, in certain improvements which I shall now describe.

If a penny be dropped down the deposit chute 18 and into the vertical passage, between 10 and 16 (path g), it will not deflect lever 20 enough to retract the undersize wire 24, because the diameter of the penny is less than that of a nickel. Consequently, in the apparatus described above the penny would be wedged between the wire 24 and the flange 12. In my modification I provide a slot 50 in the flange 12 through which the penny can pass freely, as indicated in dotted lines (path h) in Figure 3. On the outside of the flange 12 adjacent this slot I provide a sheath 52, which consists of a deep channel-shaped member attached to the flange 12 and having the correct dimensions to receive a penny.

On a pivot 54 (see Figure 1) I mount a bell-crank lever 56 having an arm 58 which carries a projection 60 extending below the sheath 52, in such a way that it normally prevents a penny from dropping out of the sheath (penny at position P¹). The lever 56 has another arm 62 which extends into engagement with the operating mechanism of the machine, the engagement being such that lever 62 is moved toward the left as viewed in Figure 1, when the machine is actuated to vend an article. Upon such a movement of the arm 62 the lever 56 will be rotated clockwise, and the resulting movement of the projection 60 will be such as to allow the penny to drop out of the sheath 52 into any suitable receptacle which may be provided for receiving the coins.

A bracket 64 is mounted on the back of the plate 10 and has upturned ears 66 and 68 in

which a wire member designated generally as 70 is pivotally mounted. A portion 72 of the wire member 70 extends between the mounting ears 66 and 68 and has an outwardly extending arm 74 carrying a weight 76 which tends to rotate the portion 72 counterclockwise as viewed in Figure 2. The arm 78 extends downwardly from the mounting ear 66 and terminates in a horizontal projecting portion 80 normally extending through a hole 82 in the plate 10 and into the normal path of a true nickel, as may be seen in Figure 3. Another arm 84 extends downwardly from the mounting lug 68 and its lower end 86 normally projects into the space at the lower end of the sheath 52 which is occupied by a penny at position P¹. With no penny in this space the weight 76 holds the projecting portion 80 of the wire member in the path of a true nickel. This projecting portion interferes with the rebound (path d) of a true coin from the anvil 44, deflecting it to the dotted position illustrated in Figure 3, causing the coin to fall along path e from position N³ into the return chute 48.

If a penny is in place (position P¹) in the sheath 52, it will displace the arm 84 of the wire member 70 into the position indicated in dotted lines in Figure 2. This will cause the arm 78 and the projecting portion 80 to be withdrawn, as best shown in Figure 4, and will permit a good nickel to rebound properly and pass through the coin outlet 46. It will be understood therefore that the selector will not keep the nickel, even a good one, unless the penny has first been deposited. When a penny has been deposited, the subsequent deposit of a good nickel will put the vending machine in operative condition. When the manual operating lever is moved to work the machine the arm 62 will be moved to the left as previously described, allowing the penny to drop into the receptacle provided for it. Similarly after the operation of the machine the nickel will also drop into a receptacle.

I arrange my device so that movement of the arm 62 toward the right in Figure 1 will accomplish a scavenging operation. The post 88 mounted on lever 56 normally is held in the bottom of a slot 90 formed in a link 92, by reason of the tension of a spring 94 which extends from the post 88 to a fastening 96 at the lower end of link 92. The post 88 is spaced on the lever 56 from its pivot point 54. Lever 56 can be rotated clockwise without affecting link 92, because post 88 merely moves upward in slot 90, but when arm 62 is moved toward the right, rotating lever 56 counterclockwise, link 92 will be pulled downwardly. The link is pivoted by rivet 98 at its top end to a lever 100, which is in turn pivoted at 102 to the mounting plate 10. A portion 104 of lever 100 extends through an opening 106 in mounting plate 10 and actuates the scavenger or clearing mechanism previously referred to, when lever 100 moves downwardly.

Movement of the arm 62 toward the right (in Figure 1) rotates the lever 56 in a counterclockwise direction, and causes the projecting portion 60 of arm 58 to move the penny back through the slot 50 (path j in Figure 3) from which it drops onto bottom 21 at position P² and then takes path k to position P³ in the coin return chute 48. Thus by manually actuating the coin return lever for the machine in such a way as to move arm 62 to the right in Figure 1, the penny which has been deposited in the machine can be returned, and any token which has been held in the selector can also be returned.

Thus if the user deposits a penny and either does not deposit a nickel or deposits a token which is rejected by the selector, he can have the penny returned.

A nickel alone will not operate the machine, but when a penny has been deposited so that a nickel can be retained, the nickel is subjected to all the customary tests; hence, a substantial part of the money received by the machine is protected by these tests.

The device is fool-proof in that the user cannot render the machine inoperative by depositing the coins in the wrong order. If he deposits his nickel first it will come back, and of course it makes a noise in the return chute which calls the user's attention to it. If he deposits his penny first the selector will subsequently accept a good nickel and make the machine operative.

The modifications which are required in a standard slug rejector are of fairly simple character and require very little in the way of additional materials. No changes in the regular actuating mechanism of the vending machine need be made. No additional coin receiving slot is necessary, so that the exterior arrangement of the vending machine case need not be altered.

It will be apparent that my invention has substantial advantages in the way of convenience and economy.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In a coin selector for a coin operated device requiring the deposit of two coins of different denominations and in a specified order to render the device operative, means receiving a coin of Y denomination and holding it temporarily at a predetermined position, means receiving a coin of X denomination, and means causing coins of X denomination to be rejected unless a coin of Y denomination is at said predetermined position said last means comprising a movable deflecting element moved from deflecting position for said coin of X denomination by being engaged by said coin of Y denomination at said predetermined position.

2. In a coin selector for a coin operated device requiring the deposit of two coins of different denominations at a predetermined position and in a specified order to render the device operative, means receiving a coin of Y denomination, means receiving a coin of X denomination, and deflecting means causing the coin of X denomination to be rejected unless a coin of Y denomination is at said predetermined position, said deflecting means having a portion in the path of movement of said coin of Y denomination, said portion being moved by the coin of Y denomination as it assumes said predetermined position and the deflecting means being thereby moved from deflecting position.

3. In a coin selector for a coin operated device requiring the deposit of two coins of different

denominations to render the device operative, means receiving a coin of Y denomination and holding it temporarily at a predetermined position, means receiving a coin of X denomination, including an anvil for the coin of X denomination to bounce from, means causing coins of X denomination to be rejected unless a coin of Y denomination is at said predetermined position, said last means being engaged by the coin of Y denomination and thereby positioned to spoil the bounce of the other coin, and a return chute to receive said other coin when the bounce is so spoiled.

4. In a coin selector for a coin operated device requiring the presence of a coin of X denomination at a predetermined position to be rendered operative, means receiving a coin of Y denomination and holding it temporarily at a predetermined position, an arm engaged and moved by the coin of Y denomination, means receiving a coin of X denomination, means movable to a position interfering with the normal path of a coin of X denomination and thereby causing it to follow a path different than that leading to said predetermined position unless a coin of Y denomination is at said predetermined position, said arm being operatively connected with said interfering means to move it from interfering position when said arm is so moved.

5. In a device of the type described, the combination of a coin deposit passageway, means directing a first coin of one denomination therefrom to a temporary position, an element at said position to be engaged by said first coin, means for directing a second coin of another predetermined denomination from said passageway on a course to a vending machine operating means, a deflector for second coin and operatively connected with said element to be rendered operable by it when so engaged by said first coin, said deflector rejecting the second coin if the first coin has not engaged said element.

6. In a device of the type described, the combination of a coin deposit chute, means directing a coin of X denomination from said chute along a path on which it has a flight in which it is constrained vertically only by gravity, means directing a coin of Y denomination from said chute along another path to a point of rest out of said first mentioned path, means normally interfering with said flight of a coin of X denomination except after such coin of Y denomination has passed to said position of rest, said means being moved to a non-interfering position with respect to said flight of the coin of X denomination by the coin of Y denomination.

7. In a device of the type described, the combination of a coin deposit passageway, means directing a coin of a predetermined denomination from said passageway on a predetermined course, normally inoperative means interfering with the passage of said coin along said course, and an element engaged by a coin of different denomination in said coin passageway before the first mentioned coin is deposited, said element being operatively connected with said interfering means to render it operative.

HARVEY T. LARIMORE.
